(57) **CLAIM**

The ornamental design for an intelligent robot, as shown and described.

DESCRIPTION

FIG. 1 is a front right side perspective view of an intelligent robot, showing my new design;

FIG. 2 is a rear left side perspective view thereof;

FIG. 3 is a front left side perspective view thereof;

FIG. 4 is a rear right side perspective view thereof;

FIG. 5 is a front elevation view thereof;

FIG. 6 is a rear elevation view thereof;

FIG. 7 is a right side elevation view thereof;

FIG. 8 is a left side elevation view thereof;

FIG. 9 is a top plan view thereof;

FIG. 10 is a bottom plan view thereof;

FIG. 11 is a front right side perspective view thereof, showing the article having the body part contracted;

FIG. 12 is a rear left side perspective view thereof, showing the article having the body part contracted;

FIG. 13 is a front left side perspective view thereof, showing the article having the body part contracted;

FIG. 14 is a rear right side perspective view thereof, showing the article having the body part contracted;

FIG. 15 is a right side elevation view thereof, showing the article in use, in which the article has a head part shown in broken lines facing right;

FIG. 16 is a right side elevation view thereof, showing the article in use, in which the article has a head part shown in broken lines facing left;

FIG. 17 is a right side elevation view thereof, showing the article in use, in which the article has a head part shown in broken lines facing upward; and,

FIG. 18 is a right side elevation view thereof, showing the article in use, in which the article has a head part shown in broken lines facing downward.

The broken lines in the drawings illustrate portions of the intelligent robot that form no part of the claimed design.

1 Claim, 18 Drawing Sheets
